ATTORNEY

UNITED STATES PATENT OFFICE.

WILLIAM D. TAM, OF JACKSON, CALIFORNIA.

COMBINATION PACKING AND DISPLAY BOX.

Application filed September 9, 1926. Serial No. 134,386.

This invention relates to improvements in box construction, my principal object being to provide a box in which the goods may be both packed for shipment and storage and 5 subsequently displayed without removing the goods or the cover from the box.

I have particularly in mind to provide a box for packing and displaying men's shirts and the like, a number of which of different 10 designs are customarily packed in superimposed order in cardboard boxes. With the type of box usually employed it is necessary when showing the shirts to a prospective customer, to take the lid off the box and remove the shirts one by one or fold them 15 back individually so that all the shirt designs can be seen. This of course not only consumes time but renders the shirts liable to become soiled or otherwise damaged by 20 the unavoidable handling thereof.

My improved box eliminates the above objectionable features as will be evident from an inspection of the drawings and a perusal of the following specification.

25 A further object of my invention is to provide a box for the purpose in which the display feature may be incorporated in a box of the ordinary construction without necessitating any radical changes being 30 made in such construction.

A further object of the invention is to produce a simple and inexpensive device and yet one which will be exceedingly effective for the purpose for which it is designed.

35 These objects I accomplish by means of such structure and relative arrangement of parts as will fully appear by a perusal of the following specification and claim.

In the drawings similar characters of reference indicate corresponding parts in the 40 several views:

Fig. 1 is a perspective elevation of my improved box.

Fig. 2 is a cross section of the box looking 45 toward the window end thereof.

Referring now more particularly to the characters of reference on the drawings, the box, of suitable rectangular form and size for its purpose, has side and end walls 1 and 2 respectively. The box is covered by a removable lid 3 which has flanges 4 overlapping the sides and ends of the box. One 50 end wall of the box is cut out for the major

portion of its area to form a window 5, which is covered by a pane 6 of substantial 55 celluloid or similar transparent material. In shirt boxes the lid flanges are usually somewhat deep, and I therefore cut away a portion of an end flange of the lid, as at 7, so that said flange will not overhang and 60 partly cover the window. This, however, is of course not necessary if the lid flanges are initially made shallow. When packing shirts in such boxes it is customary to fold the shirts transversely intermediate their ends 65 and insert them in the box in superimposed order with the fold adjacent one end wall as indicated at 9. With my improved box the shirts are placed in this order and so that the fold faces the window. In this 70 manner the design of the shirt goods is visible through the window, the depth of which is sufficient to enable all shirts to be seen from outside the box, as indicated in Fig. 75 1. It will therefore be seen that removing and handling of the shirts, in order to give the prospective customer an idea of the designs or patterns of the shirt goods, is unnecessary with my improved box.

There are various ways in which the celluloid pane may be mounted in place. I prefer, however, to make use of certain standard features of box construction for holding and locating this pane. In such boxes as ordinarily constructed the sides and bottom pieces of the box have flaps 8 at their ends, which are turned in to receive the end wall 2 of the box thereagainst. This end wall is a separate piece and is glued to the flaps. I cut the window through said end 85 wall so that its edges practically align with the inner edges of the flaps. I then utilize a portion of the space between the flaps and the end wall as grooves in which to slide the pane, the latter being inserted from the 90 top of the box. This operation is preferably performed while assembling or manufacturing the box so that the pane may be firmly held in place when the flaps are glued or pasted to the end wall.

100 It will be obvious that when a number of my improved boxes are stacked on a shelf it is possible to look directly into the boxes through the windows. Thus the number, style, or design etc. of the articles therein 105 are readily discernible. The goods can there-

fore be gone over for any purpose, selected or readily inventoried without the necessity of taking down and opening the boxes.

From the foregoing description it will be readily seen that I have produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claim.

Having thus described my invention what

I claim as new and useful and desire to secure by Letters Patent is:

A combination shipping and display box comprising side, bottom and end members, the side and bottom members having in-turned flaps to which the ends are secured, one end being cut out to form a window, the edges of the window substantially alining with the inner edges of the flaps, and a transparent pane interposed and secured between the flaps and the edges of the cut-out end. 20 25

In testimony whereof I affix my signature.

WILLIAM D. TAM.
